ILLUMINATED SIGN OR SIMILAR ARTICLE

James R. Reichow, Edina, Minn., assignor to The Cornelius Company, Anoka, Minn., a corporation of Minnesota

Filed Mar. 17, 1966, Ser. No. 1,612

Term of patent 14 years

(Cl. D1—12)

FIG. 1 is a front perspective view of an illuminated sign showing my new design.

FIG. 2 is an enlarged cross-sectional view thereof taken along line II—II of FIG. 1.

The dominant features of my design reside in the portions shown in full lines. The lettering is representative and has been shaded to indicate contrast.

This is a continuation-in-part of design application Serial No. D-79,909 filed May 11, 1964, now abandoned.

I claim:

The ornamental design for an illuminated sign or similar article, substantially as shown and described.
